UNITED STATES PATENT OFFICE.

THOMAS KEPPEL NORTH, OF WESTMINSTER, LONDON, ENGLAND, ASSIGNOR TO VICKERS
LIMITED, OF WESTMINSTER, ENGLAND.

SUBMARINE MINE.

1,318,687.

Specification of Letters Patent.

Patented Oct. 14, 1919.

Application filed October 30, 1917. Serial No. 199,388.

To all whom it may concern:

Be it known that I, THOMAS KEPPEL NORTH, a subject of the King of Great Britain, residing at Vickers House, Broad-
way, Westminster, in the county of London, England, have invented certain new and useful Improvements in or Relating to Sub-
marine Mines, of which the following is a specification.

10 This invention relates to submarine mines of the kind comprising a flotation chamber or mine proper and an anchor, sinker, or the like connected together by a rope or cable and adapted to separate by the paying
15 out of the said rope or cable after launching, the flotation chamber being provided with a number of contact arms or members which control the firing mechanism and occupy a retracted position within the flota-
20 tion chamber until after the mine is launched, whereupon, by the action of suitable de-
vices the contact arms or members are caused to protrude from the flotation chamber into a position in which they will liberate the
25 firing mechanism by contact with a passing ship.

According to this invention the aforesaid contact arms or members are rendered operative by a pull exerted when the flotation
30 chamber separates from the anchor, sinker or the like whereupon the contact arms are caused to protrude from their retracted position by means of springs normally restrained from acting by retaining devices which hold
35 the contact arms or members in their re-
tracted position and which are connected to the anchor by means of a cord, chain or the like, so that on the flotation chamber separating from the anchor, the cord will be
40 placed under tension and will exert a pull on the retaining devices, thereby releasing them and thus permitting the springs to move the contact arms or members into their protruded position for contact with a pass-
45 ing ship. Safety devices may be provided for preventing the retaining devices from becoming unintentionally released, the said safety devices being withdrawn by hand prior to the launching of the mine. Instead
50 of providing springs for causing the contact arms or members to be protruded from their retracted position, we may provide lever or other appropriate mechanism or devices

adapted to be actuated by the pull exerted on the aforesaid cord, chain or the like when 55 the flotation chamber separates from the anchor.

In order that the said invention may be clearly understood and readily carried into effect the same will now be described more 60 fully with reference to the accompanying drawing which shows the preferred embodiment of the invention and in which:—

Figure 1 is a cross sectional view of the flotation chamber of a mine constructed ac- 65 cording to the invention.

Fig. 2 is a cross sectional view on an enlarged scale of one of the contact arms or members in its extended position.

Figs. 3 and 4 are diagrammatic views 70 showing successive positions taken up by the anchor and flotation chamber prior to and after the release of the contact arms.

A is the flotation chamber, B is the anchor, C is the mooring cable, D, D are the contact 75 arms which control the release of the firing mechanism, and C', C' are the retaining devices which act to liberate the contact arms D, D.

In the example shown the upper portion 80 of the flotation chamber is provided with four of the aforesaid contact arms or mem-
bers D, D each of which comprises an inner extensible spring controlled part d telescopic-
ally located within an outer fixed part d', 85 the said inner part d up to the time of launching of the mine, being held in its re-
tracted position within the outer fixed part d' by the said retaining devices. These re-
taining devices comprise a split pin c' which 90 engages within openings c² in a flange c³ provided on a casing F surrounding the outer fixed part d' in such a manner that the pin c' extends across the face of the spring controlled inner part d and retains it in its 95 retracted position. The hand safety devices comprise a wedge-piece c⁴ which is disposed within and transversely of one end of the split portion of the pin c', the said wedge-
piece c⁴ being adapted to be withdrawn from 100 the split pin by means of a cord c⁵, one end of which is attached to the said wedge-piece c⁴ and the other end to a handle or hand grip c⁶. The split pin c' is connected to the anchor B by means of a connection c⁷, so 105 that, on the separation of the flotation chamb-

ber from the anchor, the split pin c' is automatically withdrawn by the tension exerted on the connection c' , the wedge-piece c^4 having been previously removed prior to the launching of the mine. The inner part d of the contact-arm or member is then released and moves forward under the influence of its spring d^2 until it assumes its extended position, whereupon it is locked in that position by means of a spring controlled pin d^3 carried by the outer part d' and engaging in a groove d^4 in the inner part d until it finally snaps into a locking position within an opening d^5 in the inner part d .

The firing control mechanism which it is preferred to employ may comprise cords or wires G, G^2 which are subjected to the influence of a spring G' which maintains the same under tension through the intermediary of bifurcated or stirrup-shaped levers g' each of which is pivotally mounted on the casing F surrounding each of the contact arms or members D . Each lever g' is restrained from movement by bearing against a shearable member or pin g^2 on the inner end of each of the said telescopic contact arms or members D , one of the said cords G^2 , which may be termed the tension cord, also passing around or being attached to a horizontally disposed rotary member or pulley g^3 , which normally connects the striker actuating mechanism to the flotation chamber, by means of a joint of the bayonet type and radially displaceable detents which latter have chamfered edges and engage a beveled circumferential recess formed in the striker connecting rod. The arrangement is such that the cords G, G^2 are normally maintained in a state of tension and the said rotary member or pulley g^3 is prevented from being actuated until one or other of the contact arms or members D strikes a passing ship whereupon the shearable pin g^2 appertaining to that contact arm or member is broken and liberates one of the bifurcated levers g' , thus releasing the tension on the tension cord G^2 and enabling the latter to turn the rotary member or pulley g^3 . The striker H which is of the type cocked and fired by buoyancy is then released and permitted to fire the mine in the usual manner.

Copies of this patent may be obtained for five cents each, by addressing the "Commissioner of Patents, Washington, D. C."

What I claim and desire to secure by Letters Patent of the United States is:

1. A submarine mine comprising a flotation chamber, anchoring means connected to said flotation chamber by a mooring cable, contact means on the flotation chamber which, when struck by a passing ship, bring about the actuation of the firing mechanism, said contact means normally occupying a retracted or inoperative position, and means controlled by the separation of the flotation chamber and the anchoring means after the launching of the mine which means acts to liberate said contact means so that the same assume an extended or operative position.

2. A submarine mine comprising a flotation chamber, anchoring means connected to said flotation chamber by a mooring cable, contact means on the flotation chamber which, when struck by a passing ship, bring about the actuation of the firing mechanism, said contact means normally occupying a retracted or inoperative position, retaining means for said contact means and connecting means from said retaining means to the anchoring means, said retaining means being removed by the pull which is exerted on the connecting means when the flotation chamber separates from the anchor after the launching of the mine.

3. A submarine mine comprising a flotation chamber, anchoring means connected to said flotation chamber by a mooring cable, contact means on the flotation chamber which, when struck by a passing ship, bring about the actuation of the firing mechanism, said contact means normally occupying a retracted or inoperative position, retaining means for said contact means, connecting means from said retaining means to the anchoring means, said retaining means being removed by the pull which is exerted on the connecting means when the flotation chamber separates from the anchoring means after the launching of the mine, and safety means for preventing the said retaining means from becoming unintentionally removed, said safety means being withdrawn prior to the launching of the mine.

In testimony whereof I hereunto affix my signature.

THOMAS KEPPEL NORTH.
